UNITED STATES PATENT OFFICE.

HENRY B. NICHOLS, OF PHILADELPHIA, PENNSYLVANIA, ASSIGNOR TO WILLIAM D. GHERKY, OF PHILADELPHIA, PENNSYLVANIA.

GRINDING-MACHINE.

1,096,007.

Specification of Letters Patent.

Patented May 5, 1914.

Application filed February 9, 1911, Serial No. 607,557. Renewed April 2, 1914. Serial No. 829,134.

To all whom it may concern:

Be it known that I, HENRY B. NICHOLS, a citizen of the United States, residing at Philadelphia, county of Philadelphia, and 5 State of Pennsylvania, have invented certain new and useful Improvements in Grinding-Machines, of which the following is a specification, reference being had therein to the accompanying drawing.

10 My invention relates to grinding machines, and particularly to those used for grinding railway rails in place. It is the nature of an improvement over the machines described in my prior Patent, No. 944,147, granted December 21, 1909, and my prior application Serial No. 598,840, filed December 22, 1910. In my said prior patent I show and claim a machine comprising a truck having tandem wheels adapted to run 15 on an ordinary track rail, with a reciprocating grinder mounted in slides on the truck, a motor connected to the grinder, and an outrigger secured to the truck, to maintain it upright on the rail. In my said prior 20 application I have shown and described, a similar machine having a number of improvements in matters of detail, and certain important additional features, including a pair of large wheels mounted on opposite 25 sides of the truck in such a manner as to be raised from the ground and supported on the truck during grinding, but lowered and the entire truck raised from the rail and supported upon said wheels for purposes of transportation. Certain of the 30 mechanism provided for shifting the load of the truck to the side wheels, and vice versa is claimed, including a double-acting crank which acts through gearing in both directions to raise the respective weights. The 35 crank shaft is therefore under constant tension, having a turning moment in one direction or the other. As the weights handled are considerable, any slip of the crank is 40 dangerous, and one feature of the present invention is a safety device to prevent this slip.

In both the patent and the prior application, I show the motor geared to a cam 45 drum, which acts through studs on a reciprocating rod or shaft connected to the grinder. The grinder itself in that case comprises a heavy cast holder to receive the grinding bricks, the combined masses of the 50 bricks and the holder being relied upon to

produce sufficient pressure at the grinding surface. I have found in practice that a very great strain is involved in the sudden reversal of motion of such heavy masses, and in fact it was necessary to use a specially 60 designed cam run at comparatively slow speeds, in the former structure. In the present case the necessity for such slow speeds, for any special cam, and for heavy operating parts is done away with by using 65 the weight of the machine to supply friction at the grinding surface, and making the holder for the grinding bricks as light as possible. This enables me to employ a crank shaft geared to the motor, so as to produce 70 what I may call a direct drive, at much higher speeds than heretofore practicable. While the idea broadly of transferring the weight of the machine to the grinder is not original with me, and will be claimed herein 75 only incidentally, I have rendered it effective in this type of machine, and shall claim the driving and connecting elements both broadly and specifically, together with certain features of improvement which I have 80 now introduced into the grinder itself.

Various specific features of improvement will sufficiently appear from the illustration, and from the detailed description herein-after.

85 My invention is illustrated in the accompanying drawings, wherein—

Figures 1^a and 1^b is a side elevation of the complete machine. Figs. 2^a and 2^b is a plan view thereof. Figs. 3 and 4 are opposite end views, looking in the directions of the respective arrows marked f³ and f⁴ in Fig. 2. Figs. 5 and 6 are details of the motor reducing gears and of the brick-holder, respectively. Figs. 7 and 8 are detail views of a 95 ratchet wrench appertaining to the grinder. Fig. 9 is a detail sectional view of the brick holder.

Referring to the drawings, and particularly to Figs. 1 and 2, it will be noted that the general design of the machine is the same as that disclosed in my aforesaid prior patent and application. It comprises a truck 1 having side members 1^a and end members 1^b, the side members projecting at both ends to receive journal boxes 2 for the axles of the flanged wheels 3. On one end of the truck slides 1^c are provided upon which the grinding bar or brick-holder reciprocates; at the other end of the truck a motor 4 is 110

mounted, with its armature shaft transverse to the members 1^a. The motor is connected through reducing gears 4^a, 4^b, 4^c, 5^a to the crank shaft 5, carrying the crank 5^c. This 5 crank has a crank-pin 5^d journaled in the strap bearing 6^b on one end of the connecting rod 6, the other end of which carries a similar bearing 6^a for a pin 7^p passing through lugs 7^m on one end of the brick-holder carriage 7. The details of this brick 10 carrier will be given later.

To maintain the machine upright an outrigger 8 is employed, of which however, only the broken end is shown in Fig. 2. For ease 15 of manipulation and for transportation purposes, the machine is provided with end handles 9 having handle bars 10. In transporting it, the entire weight of the machine is supported upon a pair of large wheels 20 11—12, journaled on spindles 13—14 on opposite ends of a bent axle 15. Secured upon the arch or bent portion of this axle are the separated ends of a heavy V-shaped jack lever 16 bolted to the axle shown at the ends 25 of its arms and at the other end 16^a connected through a plate 16^b with one arm 18^a of a toothed segment 18, having a hub 18^b journaled on the same spindle as the wheel 12, and driven by the intermeshing pinion 19 30 carried upon a transvers shaft 20 supported in bearings in the upper ends of opposite posts 21 riveted at their lower ends to the side members 1^a of the truck 1, and secured against angular displacement by braces 21^a. The opposite 35 ends of the shaft 20 are squared to receive the hub 22^b of a crank 22, by means of which the shaft may be operated to raise the truck upon the wheels 11—12 or to lower the truck and raise the wheels 11—12 from the ground, according to whether it is desired to move 40 the machine, or to proceed with grinding. In either case there will be a tension in one direction or the other producing a turning moment of the shaft 20, and in order to 45 maintain the parts immovable as set for either of the foregoing purposes, I secure upon the shaft a pair of ratchet wheels 20^a and 20^b, having their teeth pointing in opposite directions, and to coöperate with these 50 I provide a double dog pawl 23 having two noses 23^a and 23^b coöperating with the two ratchets, respectively. The dog is pivoted on the side member 21 so that it may be thrown over in either direction to engage 55 either ratchet at will, and thus permit motion of the crank in either direction, while locking it against motion in the reverse direction.

The ends 16^c of the jack lever are bifurcated to receive gudgeons on bearing blocks 16^d, which support eye-bolts from which depend chains 24 and 25, best shown in Fig. 4. At the lower ends these chains are connected to clevises 24^a and 25^a, bolted to ears 60 24^b and 25^b on the opposite side members 1^a

of the truck. When the segment 18 is moved downwardly as shown in Fig. 1, the ends 16^c of the jack lever are elevated as the lever and the axle turn on the hubs of the wheels 11—12, and the machine is thereby lifted 70 from the ground.

In the drawings, which have been prepared from working drawings of the machine, the jack lever 16 is shown in an intermediate or idle position, but with the segment 18 down so that if the chains 24 and 25 were attached to the ears 24^b and 25^b, the machine, comprising the truck, wheels, and attached parts, including the outrigger, would be suspended by the chains from the 80 lever 16 and supported clear of the ground on the wheels 11—12. The chains, however, are shown disconnected from the cars, for simplicity of illustration. With the machine resting on the track, and supported on the wheels 3, the chains 24 and 25 are slack and the wheels 11—12 are lifted clear of the ground and supported on the truck. This condition is brought about in the following manner: The shaft 20 is rotated in a 85 clockwise direction, so as to throw the segment 18 up until its lower end approaches the pinion 19, the pawl 23 holding it there. The end 16^a of the jack lever is thereby elevated and its ends 16^c are depressed, allowing the chains to slack up, and the projecting curved shoes 26 and 27 to rest upon studs 28 and 29 projecting from the opposite side members 1^a—1^a of the truck frame. These 95 shoes are riveted to cheek plates 30—31 connected to the ends of the arch of the axle, and thereby rigidly connected to the jack lever. The cheek plates lie upon opposite sides of a frame 32, and prevent undue oscillation of the machine when suspended 100 from the large wheels 11—12, thus performing a double function.

Turning now to Figs. 1^a and 2^a, 4 and 6, the detailed construction and arrangement of the grinding element will be described. As best shown in Fig. 6, the guide ways 1^s are secured on the upper and lower faces of side members 1^a of the frame. The carriage 7 reciprocates within the frame, its opposite sides bearing against the 115 inner faces of the guides. In order to prevent vertical displacement of the carriage either upwardly or downwardly, it is provided with slide or bearing plates 7^s, bolted to its side members at 7^b. The carriage in 120 plan (Fig. 2^a) shows the form of an open rectangle with end members 7^a carrying vertical guide flanges 7^t, forming vertical guide ways for the brick holder 33. Rigidly secured to each side of the carriage, and rising above it, is a post 7^e, these posts having journaled in their upper ends the transverse rockshaft 7^d, through which is threaded the stem of the vertical pressure screw 34, provided with a T-head 34^a and lock nuts 34^b. 130

Rising from each end of the brick holder (Fig. 1^a) is a post 33^a, and extending longitudinally across the heads of these posts is an arched reinforced leaf spring 35, having its ends fitted over transverse rods extending across slots in the post, or otherwise secured, as by covering caps, so as to prevent accidental displacement. At its middle, a saddle 35^s is bolted on the spring, which receives the thrust from the lower end of the pressure screw 34, in a manner which will be hereinafter fully explained. The pressure screw can be turned, turning the rockshaft with it, so as to remove the foot 15 of the screw from its socket in the spring saddle, which leaves the brick-holder free to rise in its slides between the flanges 7^t.

In order that the motion of the rockshaft may positively raise the brick-holder from its grinding position, I provide a pair of stub lever arms 36, secured rigidly on the opposite ends of the rockshaft, as best shown in Figs. 1^a, 2^a and 6. Each of these arms carries a clevis at its extremity from which depends a chain 36^a, the other end of which is carried down and secured at 36^b to the brick-holder. In order that these chains may not rattle and thereby create a disturbance when operated at night, also in order to prevent fouling of the links, I provide a spring 36^c for each chain, one end of said spring being secured about the middle of the chain, and its other end secured to a post or stud on the carriage. In passing it should be noted that similar springs may be and preferably are employed in connection with the chains 24 and 25, constituting anti-rattling devices, which I shall claim herein as part of my invention. In order to prevent the brick-holder from dropping after it has been elevated by turning the rockshaft, a toothed detent arc 37 is also fixed on the shaft, with which co-operates a pawl 38, held in engagement by a spring 39, but readily disengaged by manually lifting its heel. Thus, by merely turning the screw 34 in the rockshaft, and then rotating the shaft, three things are accomplished, viz., the pressure is removed from the spring 35, the brick-holder is lifted by means of the chain, and the parts are held locked by the pawl and ratchet. The degree of pressure on the spring, or in other words, the proportion of the weight of the machine which will be imposed upon the brick-holder, and hence the pressure on the frictional surface of the bricks, is determined by adjustment of the screw 34, which can be turned in the rockshaft after loosening the two lock nuts 34^b. 60 These nuts are not essential however.

The operation of my machine as thus described is as follows: When the machine is first brought out for use, and in order to convey it to the point of use, the segment 65 18 is cranked down into the position shown

in Fig. 1, and the entire machine thereby lifted clear of the ground. As the segment swings down the shoes 26 and 27 slide over their studs 28 and 29, and the arch of the axle rises while the axle as a whole falls 70 until the tires of the large wheels strike the ground, after which the same motion continues, the shoes leave the studs, the chains 24 and 25 become taut, and begin to lift the weight of the truck. During this motion the axle is maintained in alinement by a pair of side links 40 and 41 having terminal eyes fitted to the shaft 20 and the spindles of the axle, respectively. At the end of the motion the machine hangs from the chains, the 75 cheek plates guard opposite sides of the frame 32 to prevent oscillation, and the device may then be moved by means of the handle-bars 10. Having been adjusted with the small wheels 3 over the track rail to the 80 ground, the crank handle 22 is grasped, the pawl 23 is thrown off, and the motion of the crank is reversed to rotate the pinion 19 clockwise and permit the segment 18 to rise. This lifts the ends 16^a of the jack lever, 85 lowers the ends 16^c, and permits the truck to descend until the wheels 3 rest on the rail and take the weight of the truck. Continuance of this motion renders the chains 24 and 25 slack, brings the shoes 26 and 27 onto their roller studs 28 and 29, and with these studs as fulcrums lifts the wheels 11 and 12 and their attached parts as already stated. The brake lever 43 is then thrown up to depress the brake 42 into contact with the rail, 90 the pawl 38 of the grinding element is thrown off, the pressure screw 34 is turned in the position shown in Fig. 1^a, (the brick-holder being lowered thereby) and the 95 motor may be started to proceed with the 100 grinding, the screw 34 being turned to regulate the pressure.

It will be observed that a salient difference between this machine and those described in my prior patent and application lies in this, that whereas in the prior machines a heavy grinding body was reciprocated, with great inertia to overcome at the end of every stroke, in the present case the brick-holder and carriage are light, with relatively small inertia, and may be operated at correspondingly higher speed. The pressure necessary to insure efficient grinding is secured by tension of the spring 35, whose downward thrust is exerted against the posts 33^a and communicated thereby through the body of the holder 33 to the bricks; and whose upward thrust is exerted against the screw 34, and communicated thereby to the posts 7^c, and thence to the side 110 members of the carriage and through the lower slide plates 7^s to the slides 1^s on the side members 1^a of the truck frame. Since the contact between the slide plate 7^s and the slide 1^s is constant during reciprocation, it 115 120 125 130

follows that the weight of the machine is imposed to the desired degree upon the spring 35 and so upon the bricks equally throughout their entire travel; while at the 5 same time the actual moving mass is small. Another result which flows from this arrangement is that a brake such as that shown at 42 is not always essential. The machine being very heavy, its own inertia assists in 10 keeping it steady on levels, under control of hand-grip on the bars 10. It is desirable in this machine to use the brake sparingly, as it tends to remove working pressure from the grinder.

15 To remove the machine from the rail, the motions of the cranks, pinion 19, segment 18, and jack lever 16 are reversed, as previously stated, the T handle of the screw 34 being first thrown over to disengage the 20 screw from the spring 35, and to lift the brick-holder 33.

It remains to describe the mechanism by which accidental rotation of the crank 22 is prevented. This is shown in Figs. 1^b and 2^b but is most clearly illustrated in Fig. 7. The crank is provided with a split handle, one-half of which 22^a is fixed, and the other half 22^b is pivoted at 22^d, with a projecting short lever arm 220^b to which is pivotally connected the outer end of a slide rod 22^e, which carries a locking dog 22^f at its extremity, normally forced by a spring 22^g into engagement with the periphery of a square toothed disk 20^a fixed on one of the 30 posts 21. The locking dog engages the disk at all times, except when the handle is grasped, when the pivoted portion 22^b is forced toward the fixed portion 22^a, and moves the slide rod so as to withdraw the 35 dog 22^f from the teeth of the disk.

The brick-holder 33, as shown in Figs. 1^a, 2^a and 6, is in the form of an open rectangle, with side plates 33^a and 33^b, between which the bricks 330 are held with interposed 45 shims, being jammed longitudinally against the ends of the holder when adjusted, by means of a wedge 33^w forced down between opposite wedge-faced shims, by means of a screw 33^s working in a bridge 33^x across the 50 side plates 33^a and 33^b. The screw has a squared head 33^h, to take a wrench such as that shown in Figs. 8 and 9, wherein a socket head is acted upon through ratchet teeth around its body by a double-acting pawl 55 lever.

Having thus described my invention, what I claim and desire to secure by Letters Patent is:

1. In a rail grinding machine, a truck 60 frame, guide ways thereon, tandem track wheels alining the frame and said guides a brick-holder adapted to reciprocate on said ways, a plurality of vertically adjustable grinding bricks in said holder a motor on the truck, a crank shaft and a crank adja-

cent to the motor, an operating connection between the motor and the crank shaft, and a connecting rod having a pivotal connection with the crank pin at one end, and with the brick-holder at the other the arrangement being such that the brick holder is secured to the truck frame against vertical displacement, and the wear in grinding is taken up by vertical adjustment of the bricks in the holder.

2. In a rail grinding machine, a truck frame, guide ways thereon, tandem track wheels alining the frame and said guides a brick-holder adapted to reciprocate on said ways, a plurality of vertically adjustable grinding brick in said holder a motor on the truck, a crank shaft and a crank adjacent to the motor, reducing gears between the motor and the crank shaft, and a connecting rod having a bearing to receive the crank pin at one end, and connected to the brick-holder at the other end the brick holder being vertically adjustable in the guides, but secured thereon during grinding by upper and lower flanges to prevent vertical displacement and insure grinding pressure.

3. In a rail grinding machine, truck frame, guide ways thereon, tandem track wheels alining the frame and said guides, a brick-holder adapted to reciprocate on said ways, a plurality of vertically adjustable grinding bricks in said holder a motor on the truck, a crank shaft and a crank adjacent to the motor, an operating connection between the motor and the crank shaft, a connecting rod having a pivotal connection with the crank pin at one end, and with the brick-holder at the other, and means traveling with and exerting pressure on the 105 brick-holder so as to produce pressure at the grinding surface disproportionate to the mass of said holder the brick holder being vertically adjustable in the guides, but secured thereon during grinding by upper and lower flanges to prevent vertical displacement and insure grinding pressure.

4. In a rail grinding machine, a truck frame, guide ways thereon, tandem track wheels alining the frame and said guides a brick-holder adapted to reciprocate on said ways, a plurality of vertically adjustable grinding bricks in said holder a motor on the truck, a crank shaft and a crank adjacent to the motor, reducing gears between the motor and the crank shaft, a connecting rod having a bearing to receive the crank pin at one end, and connected to the brick-holder at the other end, and means also reciprocating on the ways and adapted to be 115 adjusted to exert pressure on the brick-holder so as to produce pressure at the grinding surface disproportionate to the mass of said holder said pressure means being provided with upper and lower flanges

engaging the upper and lower faces of the guide ways so as to prevent vertical displacement and furnish resistance to the pressure through the truck frame.

5. In a rail grinding machine, a truck frame, guide ways thereon, tandem track wheels alining the frame and said guides a brick-holder adapted to reciprocate on said ways, a motor on the truck, a crank shaft 10 and a crank adjacent to the motor, an operating connection between the motor and the crank shaft, a connecting rod having a pivotal connection with the crank pin at one end, and with the brick-holder at the other, and 15 adjustable means also reciprocating on said ways adapted to superimpose a portion of the weight of the machine upon the brick-holder in its travel.

6. In a rail grinding machine, a truck frame, guide ways thereon, tandem track wheels alining the frame and said guides a brick-holder adapted to reciprocate in said ways, a motor on the truck, a crank shaft and a crank adjacent to the motor, an operating connection between the motor and the crank shaft, a connecting rod having a pivotal connection with the crank pin at one end, and with the brick-holder at the other, a spring bridged over and connected to the brick-holder, and means traveling on the truck frame for exerting pressure on said spring to compress the same.

35 7. In a rail grinding machine, a truck frame, a pair of parallel horizontal guide ways thereon, a carriage fitted for reciprocation in said guides, with means thereon to prevent vertical displacement of the carriage, a brick holder adapted for vertical movement in the carriage, grinding bricks carried in said holder, tandem track wheels 40 alining the truck frame and brick holder over the rail to be ground, a motor on the truck frame, reducing gears and a crank shaft and connecting rod for transmitting power from 45 said motor to the sliding carriage and brick holder, and means secured upon the carriage and traveling therewith, adapted to exert variable pressure on the brick holder.

8. In a rail grinding machine, a truck frame, a pair of parallel horizontal guide ways thereon, a carriage fitted for reciprocation in said guides, with means thereon to prevent vertical displacement of the carriage, a brick holder adapted for vertical movement in the carriage, grinding bricks carried in said holder, tandem track wheels alining the truck frame and brick holder over the rail to be ground, a motor on the truck frame, reducing gears and a crank shaft and connecting rod for transmitting power from said motor to the sliding carriage and brick holder, and means for exerting pressure on the brick holder in grinding comprising a member secured to the brick holder, a second bridge member se-

cured to the carriage; and an adjustable connection between said members.

9. In a rail grinding machine, a truck frame, a pair of parallel horizontal guide ways thereon, a carriage fitted for reciprocation in said guides, with means thereon to prevent vertical displacement of the carriage, a brick holder adapted for vertical movement in the carriage, grinding bricks carried in said holder, tandem track wheels aligning the truck frame and brick holder over the rail to be ground, a motor on the truck frame, reducing gears and a crank shaft and connecting rod for transmitting power from said motor to the sliding carriage and brick holder, and means for exerting pressure on the brick holder during grinding comprising a spring bridged from end to end of the brick holder, a transverse bridge secured on the carriage, and a pressure screw threaded through said bridge so as to bear against said spring. 70 75 80 85

10. In a rail grinding machine, a truck frame, a pair of parallel horizontal guide ways thereon, a carriage fitted for reciprocation in said guides, with means thereon to prevent vertical displacement of the carriage, a brick holder adapted for vertical movement in the carriage, grinding bricks carried in said holder, tandem track wheels alining the truck frame and brick holder over the rail to be ground, a motor on the truck frame, reducing gears and a crank shaft and connecting rod for transmitting power from said motor to the sliding carriage and brick holder, and means for regulating the pressure on the grinding surface comprising a pair of end posts uprising from the brick holder, a pair of side posts uprising from the carriage, a bridge bar extending across the upper ends of said carriage posts, a spring extending thereunder connecting the upper ends of the brick holder posts, and a pressure screw threaded through said bridge bar and bearing down against the said spring, whereby vertical pressure may be applied from the truck frame through the guide ways and the carriage to the brick holder and the grinding surface. 90 95 100 105 110 115

11. In a rail grinding machine, a truck frame, a pair of parallel horizontal guide ways thereon, a carriage fitted for reciprocation in said guides, with means thereon to prevent vertical displacement of the carriage, a brick holder adapted for vertical movement in the carriage, grinding bricks carried in said holder, tandem track wheels alining the truck frame and brick holder over the rail to be ground, a motor on the truck frame, reducing gears and a crank shaft and connecting rod for transmitting power from said motor to the sliding carriage and brick holder, and means for exerting pressure upon the grinding surface in 120 125 130

- operation, and for raising the brick holder out of grinding position, comprising the following: a pair of end posts 33^a uprising from the brick holder, a pair of side posts 5 7^e uprising from the carriage, a spring 35 extending longitudinally between the side posts and having its ends connected to said end posts, a bridge bar 7^d extending across and pivotally secured in the upper ends of 10 the side posts, a pressure screw 34 threaded into said bridge bar and provided with suitable locking means, the lower end of said screw bearing on the spring 35, one or more projecting fingers 36 on said bridge bar, and 15 lifting means 36^a extending from said fingers to the brick holder, whereby during grinding the pressure screw 34 may be caused to transfer part of the weight of the machine through the guide ways and the 20 sliding carriage to the brick holder, and when it is desired to raise the brick holder, the pressure screw may be unscrewed, the bridge bar 7^d turned on its axis, and the brick holder lifted through the means 36^a. 25 12. In a machine of the class described, a frame, grinding means thereon, and a chain connection, together with a takeup spring connecting said chain transversely to its

length to a fixed portion of the machine, whereby rattling of the chain in operation 30 is prevented.

13. A rail grinding machine comprising a truck frame, a grinding element, means on the frame adapted to support it over the rail to be ground, auxiliary means to support the entire machine clear of the rail for transportation purposes, and means to shift the weight of the frame to the grinding element from the auxiliary means or to the auxiliary means from the grinding element, 40 at will.

14. A rail grinding machine comprising a truck frame, a grinding element, means to support the frame over the rail to be ground, auxiliary wheels to support the entire machine in transportation, and means to shift the weight of the machine to the auxiliary wheels or the weight of the auxiliary wheels to the frame and the grinding element, at will. 50

In testimony whereof I affix my signature in presence of two witnesses.

HENRY B. NICHOLS.
